UNITED STATES PATENT OFFICE

RICHARD R. MEAD, OF QUEENS VILLAGE, NEW YORK, ASSIGNOR TO MERGENTHALER LINOTYPE COMPANY, A CORPORATION OF NEW YORK

TYPOGRAPHICAL COMPOSING MACHINE

Application filed December 21, 1929. Serial No. 415,643.

This invention relates to typographical composing machines, such as Linotype machines of the general organization represented in U. S. Letters Patent to O. Mergenthaler, No. 436,532, wherein circulating matrices are released from a magazine in the order in which their characters are to appear in print and then composed in line, composed line presented to a mold for the casting of a slug or Linotype bearing printing characters corresponding to those of the matrices, and the matrices thereafter returned by a distributing mechanism to the magazine from which they started.

In these machines, the matrices are released from their storage magazine by means of a series of escapements operated by power under the control of finger keys, said escapements each presenting a centrally pivoted lever and front and rear pawls arranged to be projected alternately into the corresponding magazine channel in controlling the release of the matrices therefrom, one at a time. Ordinarily springs are employed to actuate the escapement levers in one direction and to hold them at rest with one of the pawls (usually the front pawl) projected into the magazine, while the key-controlled power devices serve to actuate the escapement levers in the opposite direction against the action of the springs to reverse the position of the pawls temporarily in order to release the leading matrix of a column and arrest the following matrix. In the commercial machines of the model 8 or model 14 class, the actuation of the escapement levers by the power devices is effected thru the medium of small plungers slidable fore-and-aft of the magazine and forming part of the escapement mechanism, these plungers being mounted in a so-called "escapement bar" which houses the escapement mechanism, but which leaves the forward ends of the plungers exposed for engagement with the power devices (see for example the Rogers Patent No. 1,109,872).

In some instances the escapement mechanism is mounted independently of the magazine, as in the Rogers patent just mentioned, while in other instances it is attached to or

carried by the magazine. In the former case, i. e. when the escapement mechanism is unattached to the magazine, the matrices must be locked in the magazine before the latter can be removed from the machine, as otherwise the matrices would run out of the magazine or "spill"; whereas in the latter case, i. e. when the escapement mechanism is carried by the magazine, it is not absolutely necessary to lock the matrices in the magazine before its removal, because the escapements (in machines of the model 8 or model 14 class, altho not in machines of all classes) will serve to confine the matrices within the magazine when removed. However, in relying upon the escapements to prevent the matrices from leaving the magazine, care must be taken not to actuate the escapements during the handling of the magazine, as for example during its removal from or replacement in the machine, or in transporting it to and from its place of storage. In other words, the escapements do not actually lock the matrices in the magazine, but serve only to prevent them from running out so long as they (the escapements) are not touched or tampered with.

In actual practice, it has been found that few operators or machine attendants exercise the necessary care in handling magazines equipped with escapements to avoid spilling of the matrices, and especially when the escapement mechanism is of the kind employed in the model 8 or model 14 machines, or as illustrated in the Rogers patent above referred to. Besides, the magazines are rather heavy and awkward to take hold of, and it frequently happens that the attendant will push rearwardly on the escapement actuating plungers (whose forward ends, it will be remembered, protrude beyond the lower or front end of the magazine) and, by the consequent actuation of the escapement levers, release matrices from a number of the magazine channels. In fact the same result will follow from other causes not attributable to carelessness or inattention on the part of the operator, there being many occasions when the escapements are accidentally or unintentionally actuated while the

magazine is in use in the machine or out of use.

The present invention is intended to obviate the foregoing and other difficulties and 5 contemplates a simple form of locking device which may be carried by the magazine and which will cooperate with the escapements to prevent their actuation except when the magazine occupies an operative position 10 in the machine. In the embodiment illustrated, the locking device is in the form of a notched plate which is adjustable longitudinally in opposite directions to locate its notches in or out of registry with depending 15 lugs on the forward ends of the escapement plungers, the plate in the former position permitting the plungers to be pushed rearwardly in actuating the escapement levers and in the latter position positively locking 20 the plungers against rearward movement and thereby preventing the operation of the escapement levers. This locking plate is mounted in the escapement bar directly below the escapement plungers and protrudes 25 beyond one end thereof for engagement with a stationary cam mounted on the machine frame. Normally, a spring attached to the locking plate serves to hold it in its locking position, but when the magazine is brought 30 into its operative position in the machine, the stationary cam adjusts the plate endwise against the action of the spring to locate it in its unlocking position.

In the accompanying drawings, the invention has been shown as applied to a machine equipped with a plurality of magazines movable upwardly and downwardly in the machine to bring any selected one into operative position, and hence the stationary 35 cam above referred to is made to engage and actuate the locking plate of each magazine as the latter is moved into operative position. It will be understood of course that when any one of the magazines is moved out of operative position, its locking plate, being carried free of the stationary cam, will be adjusted instantly to locking position by the attached spring. Ordinarily the magazines are removed from the machine when they are 40 out of operative or composing position, so that the locking of the escapements by the movement of the magazine from operative position will answer all purposes. In the case of a single magazine machine, the movement of the magazine from operative position would also serve to effect the locking of the escapements, whether this movement be one preparatory to the actual removal of the magazine, as is usually the case, or one incidental to the removal of the magazine.

Some of the modern machines are provided with a plurality of main magazines alone, as in the model 8, or with a plurality of side or auxiliary magazines in addition 45 to the main magazines, as in the model 14.

The above described improvements are obviously applicable to either kind of machine, altho it may be stated that they are herein shown in connection with the side or auxiliary magazines.

Referring to the drawings:

Fig. 1 is a side elevation of a shifttable multiple magazine machine equipped with the present improvements;

Fig. 2 is a vertical longitudinal section taken thru the parts shown in Fig. 1;

Fig. 3 is a vertical transverse section, on an enlarged scale, taken thru the escapement bar and showing the manner of operation of the escapement locking plate; and

Fig. 4 is a bottom plan view of the parts shown in Fig. 3.

The matrices X are stored according to font or set in a plurality of magazines A, two of which are shown herein, but of which a greater or less number may be employed as desired. The magazines A are removably mounted in a shift frame A¹ which is arranged to be moved upwardly and downwardly in the machine frame to bring one or the other of the magazines into operative position. In Fig. 1 the lower magazine is shown in such operative position, while in Fig. 2 the upper magazine is shown in operative position. In removing the magazines, the one to be removed is first shifted out of operative position, if need be, in order to locate it above the assembler entrance B as in the case of the upper magazine in Fig. 1.

Each of the magazines A is equipped with an escapement mechanism which, when the magazine is in operative position, is adapted to control the release of the matrices therefrom in response to the actuation of the keyboard. This escapement mechanism (see Fig. 2) comprises as usual a series of centrally pivoted levers C, each provided with front and rear matrix-engaging pawls C¹ and C², a corresponding series of blade springs C³ bearing upon rearward extensions C⁴ of the levers C, and a corresponding series of fore-and-aft sliding plungers C⁵ arranged with their rear ends in engagement with downward extensions C⁶ of the escapement levers. All of these parts are mounted in a suitable supporting frame or "escapement bar" D attached to the magazine and which completely encloses the various parts except for the forward ends of the sliding plungers C⁵, which are exposed or located outside of the escapement bar for engagement with the key-controlled power operated levers E. In this connection, it may be noted that the escapement plungers C⁵ are formed at their forward ends with depending lugs e to facilitate their engagement with the levers E.

Normally, or when the parts are at rest, the matrices are confined within the maga-

zine by the front pawls C^1 due to the action of the springs C^3 which, by pressing downwardly upon the rear ends of the escapement levers C , hold these pawls projected into the magazine channels. Upon the actuation of a finger key, however, the corresponding escapement plunger C^5 is pushed rearwardly by the lever E to reverse temporarily the position of the escapement, the front pawl C^1 by such action being withdrawn from the magazine channel to permit the release of the leading matrix, and the rear pawl C^2 being projected into the magazine channel to intercept the following matrix, which now becomes the leading one. Thereafter, the spring C^3 restores the escapement to its original position so as to withdraw the rear pawl C^2 from the magazine channel and project the front pawl C^1 back into the channel, the intercepted matrix thus being allowed to slide forwardly into engagement with the front pawl for release thereby upon the next actuation of the finger key.

All of the foregoing parts and their mode of operation are well known and need no further description, but if further particulars are desired reference may be had to the Rogers Patent No. 1,109,872 above referred to.

In carrying out the present invention, each of the magazines is provided with a locking device to prevent the accidental or unintentional operation of the escapements when the magazine is out of operative position. In the preferred embodiment illustrated, the locking device is in the form of a longitudinally adjustable plate F attached to the underside of the escapement bar D directly below the escapement plungers C^5 . As a simple and convenient means of attachment, there are employed two set screws F^1 , one at each end of the locking plate, passing thru elongated slots F^2 formed in the plate. At its forward edge, the locking plate is formed with a series of cuts or notches F^3 corresponding in number, spacing and width with the depending lugs c formed on the forward ends of the escapement plungers C^5 . The extent of the longitudinal adjustment of the locking plate is such that when the plate is shifted in one direction, the notches F^3 will be located in registry with the lugs c in order to permit the rearward movement of the plungers in actuating the escapements, and when the plate is shifted in the opposite direction, the notches will be located out of registry with the lugs c in order that the intermediate or solid portions F^4 of the plate will lie behind the lugs c and thus prevent the rearward or escapement actuating movement of the plungers. In this way, by adjusting the locking plate in one direction or the other,

the escapements may be locked or unlocked as desired.

While the locking plates F might be adjusted by hand in effecting the locking or unlocking of the escapements, it is proposed, according to this invention, to effect their adjustment automatically and in such manner that the escapements will always be locked against actuation except when the respective magazines are in operative position in the machine. In effecting such automatic adjustment of the locking plates, means are provided for shifting them to locking position and unlocking position as the corresponding magazines are moved out of and into operative position respectively, and this whether such movement of the magazines be merely for purposes of interchange or preparatory to the removal of one or another of them.

By reference to Fig. 3, it will be noted that each of the locking plates at the right has an upturned or right angular portion F^5 acted upon by a compression spring G^1 confined within the escapement bar D and which serves normally to shift the plate to and hold it in its active or locking position. To the outer face of the right angular portion F^5 , there is attached a cam element G protruding beyond the end of the escapement bar for engagement with a cooperating cam element H carried by a supporting bracket H^1 screwed or otherwise secured to the fixed machine frame (see Fig. 1). These cam elements G and H , which are hardened to resist wear, are so arranged that when brought into engagement with each other by the movement of the corresponding magazine into operative position, they will adjust the locking plate F to its inactive or unlocking position, being formed with straight or parallel faces G^2 and H^2 respectively, which determine the proper location of the plate and insure the proper registry of its notches F^3 with the depending lugs c of the escapement plungers C^5 .

The operation of the parts will now be entirely clear: When either of the magazines A is out of operative position, as in the case of the upper magazine in Fig. 1 or the lower magazine in Fig. 2, the spring G^1 holds the corresponding locking plate F to the right or in its locking position; but when either of the magazines is in operative position, as in the case of the lower magazine in Fig. 1 or the upper magazine in Fig. 2, the coacting cam elements G and H hold the corresponding locking plate to the left or in its unlocking position (see Figs. 3 and 4). As before stated, the shifting of the locking plate to its active or inactive position takes place automatically with the movement of the corresponding magazine from and to its operative position, the spring G^1 effecting the locking adjustment of the

plate immediately the magazine leaves its operative position, and the cam elements G and H effecting the unlocking adjustment of the plate as the magazine is brought into operative position. As a result, the escapements of the magazines are always locked except when the magazines are in use, and hence all liability of spilling the matrices from the magazine is effectively guarded against.

In order to protect the locking plates F against accidental operation when the magazines are out of use, each of the magazines is provided with a guard member J which is attached to the escapement bar D in position to cover or shield the cam element G. In the form illustrated, the guard member is bifurcated or forked to provide clearance for the cam elements G and H when the magazine is moved into and out of operative position.

In removing the magazines, if the one to be removed happens to be located at the time in operative position, the shift frame A¹ is first moved upwardly to carry said magazine out of operative position and locate it above the level of the assembler entrance B, so that whether the movement of the magazines be for interchange or removal the same locking action takes place. As a matter of fact however, even if the magazine were removed by lifting it directly by hand from its operative position, the escapements would be locked automatically in the same way, due to the fact that the cam element G is carried out of engagement with the cooperating stationary cam element H. It is obvious therefore that this invention is as applicable to single magazine machines as to multiple magazine machines, and this whether the magazines are first moved mechanically from operative position before removal or not.

The invention has been shown herein merely in preferred form and by way of example and many alterations and modifications, both in mode of application and embodiment, will readily suggest themselves to those skilled in the art without departing from the spirit of the invention. It should be understood therefore that the invention is not limited to any specific form or embodiment, except insofar as such limitations are specified in the appended claims.

Having thus described my invention, what I claim is:

1. In or for a typographical composing machine, a matrix magazine equipped with a series of matrix releasing escapements and with a longitudinally adjustable locking plate to cooperate with said escapements in preventing or permitting their actuation.

2. In or for a typographical composing machine, a matrix magazine equipped with a series of matrix releasing escapements and

with a locking plate formed in one of its edges with a corresponding series of notches, said locking plate being adjustable longitudinally in opposite directions to locate its notches in or out of registry with the escapements so as to permit or prevent their actuation. 70

3. In or for a typographical composing machine, a matrix magazine equipped with an escapement mechanism presenting a series of actuating plungers and with a sliding locking plate adjustable into or out of engagement with said escapement plungers in preventing or permitting the operation 75 of the escapement mechanism. 80

4. In or for a typographical composing machine, a matrix magazine equipped with an escapement mechanism presenting a series of actuating plungers and with a locking plate formed in one of its edges with a corresponding series of notches, said locking plate being adjustable longitudinally in opposite directions to locate its notches in or out of registry with the escapement plungers in permitting or preventing the operation 85 of the escapement mechanism. 90

5. In or for a typographical composing machine, a matrix magazine equipped with an escapement mechanism presenting a series of actuating plungers slidable fore-and-aft of the magazine and formed at their forward ends with depending lugs and with a transverse locking plate arranged below the escapement plungers at the rear of their depending lugs, said plate being adjustable 95 to locate its forward edge into or out of engaging relation to said plunger lugs whereby to prevent or permit the operation of the escapement mechanism. 100

6. In or for a typographical composing machine, a matrix magazine equipped with an escapement mechanism presenting a series of actuating plungers slidable fore-and-aft of the magazine and formed at their forward ends with depending lugs and with a transverse locking plate arranged below the escapement plungers at the rear of their depending lugs, said plate being adjustable longitudinally in opposite directions to locate its forward edge into or out of engaging relation to said plunger lugs whereby to prevent or permit the operation of the escapement mechanism. 110 115

7. In or for a typographical composing machine, a matrix magazine equipped with an escapement mechanism presenting a series of actuating plungers slidable fore-and-aft of the magazine and formed at their forward ends with depending lugs and with a transverse locking plate arranged below the escapement plungers at the rear of their depending lugs; said plate being notched in its forward edge and adjustable longitudinally 120 125 in opposite directions to locate its notches 130

in or out of registry with the plunger lugs in permitting or preventing the operation of the escapement mechanism.

8. In or for a typographical composing machine, a matrix magazine equipped with an escapement bar containing a series of matrix releasing escapement levers spring-actuated in one direction and a corresponding series of fore-and-aft slidable plungers for actuating the escapement levers in the opposite direction, said escapement plungers having their forward ends exposed, and with a transverse locking plate mounted on the escapement bar and adjustable longitudinally in opposite directions into and out of engaging relation to the escapement plungers, said locking plate protruding at one end beyond the escapement bar for engagement with suitable adjusting means.

9. In or for a typographical composing machine, a matrix magazine equipped with an escapement bar containing a series of matrix releasing escapement levers spring-actuated in one direction and a corresponding series of fore-and-aft slidable plungers for actuating the escapement levers in the opposite direction, said escapement plungers having their forward ends exposed, and with a transverse locking plate mounted on the escapement bar and adjustable longitudinally in opposite directions into and out of engaging relation to the escapement plungers, said locking plate being spring-actuated in one direction and protruding at one end beyond the escapement bar for engagement with suitable means for actuating it in the opposite direction.

10. A matrix magazine according to claim 8, equipped further with a fixed guard member overlying the protruding end of the locking plate to protect it against accidental operation.

11. In a typographical composing machine, the combination of a matrix magazine movable into and out of operative position, said magazine being equipped with a series of matrix releasing escapements and with adjustable means for preventing or permitting their actuation, and means whereby the movement of the magazine from and to operative position automatically effects the adjustment of the first said means so as to prevent and permit the actuation of the escapements respectively.

12. In a typographical composing machine, the combination of a matrix magazine movable into and out of operative position, said magazine being equipped with a series of matrix releasing escapements and with adjustable locking means to prevent or permit their actuation, and means whereby the movement of the magazine from and to operative position automatically effects the adjustment of said locking means to active and inactive position respectively.

13. In a typographical composing machine, the combination of a matrix magazine movable into or out of operative position, said magazine being equipped with an escapement mechanism presenting a series of 70 actuating plungers slidable fore-and-aft and with a locking plate adjustable into and out of engaging relation to said escapement actuating plungers, and means whereby the movement of the magazine from and to operative position automatically effects the adjustment of the locking plate to active and inactive position respectively.

14. In a typographical composing machine, the combination of a magazine movable into or out of operative position, said magazine being equipped with a series of matrix releasing escapements and with a longitudinally adjustable locking plate to cooperate with said escapements in preventing or permitting their actuation, and means whereby the movement of the magazine from and to operative position automatically effects the adjustment of the locking plate to active and inactive position respectively.

15. A combination as in claim 14, characterized by the fact that the automatic adjusting means comprises a spring for adjusting the locking plate in one direction and a stationary cam for adjusting it in the opposite direction, said cam being mounted on the fixed machine frame and arranged to be engaged with and disengaged from the locking plate as the magazine is moved to and from its operative position respectively.

16. A combination as in claim 14, characterized by the fact that the locking plate therein referred to is formed in one of its edges with a series of notches which are shiftable into and out of registry with the escapements as the plate is adjusted automatically in opposite direction.

17. In a typographical composing machine, the combination of a plurality of magazines movably mounted in the machine frame so that any selected one thereof may be brought into operative position, each of said magazines being equipped with a series of matrix releasing escapements and with adjustable means for preventing or permitting their actuation, and means whereby the movement of a selected magazine from and to operative position automatically effects the adjustment of the first said means so as to prevent and permit the actuation of the escapements respectively.

18. In a typographical composing machine, the combination of a plurality of magazines movably mounted in the machine frame so that any selected one thereof may be brought into operative position, each of said magazines being equipped with a series of matrix releasing escapements and with a locking plate adjustable into and out of engaging relation to said escapements, and

means whereby the movement of a selected magazine from and to operative position automatically effects the adjustment of the locking plate to active and inactive position respectively.

19. In a typographical composing machine, the combination of a plurality of magazine movably mounted in the machine frame so that any selected one thereof may be brought into operative position, each of said magazines being equipped with a matrix releasing mechanism presenting a series of actuating plungers and with a longitudinally adjustable locking plate to cooperate with said plungers in preventing or permitting the actuation of the escapement mechanism, and means whereby the movement of a selected magazine from and to operative position automatically effects the adjustment of the locking plate to active and inactive position respectively.

20. A matrix magazine according to claim 1, equipped further with a guard member to prevent the accidental operation of the adjustable locking plate.

21. A matrix magazine according to claim 3, equipped further with a guard member to prevent the accidental operation of the adjustable locking plate.

22. In testimony whereof, this specification has been duly signed by:

RICHARD R. MEAD.
